STERILIZING MEANS

Charles R. Meitzler, Rochester, N. Y., assignor
to Oscar H. Pieper and Alphonse F. Pieper,
Rochester, N. Y.

Application October 30, 1931. Serial No. 571,953

8 Claims. (Cl. 167—3)

This invention relates to sterilizing means, and more particularly to sterilizers adapted for use in dental offices and similar places.

The present invention is in the nature of an improvement over the sterilizer disclosed in my co-pending application, Serial No. 478,838, filed August 28, 1930. In the sterilizer of said co-pending application, I have provided a water tank which communicates with the sterilizing tanks, and a removable water container for supplying water to the water tank when the water therein falls below a predetermined level. I have also disclosed, in such co-pending application, heating means for the sterilizing tanks and means for automatically disabling such heating means when the water in the water tank falls below a predetermined level, the heating means being restored to operative condition when the water level in the water tank is restored to normal. While the sterilizer of my co-pending application is highly efficient, I find that it can be rendered even more efficient by providing means for supplying water to the water tank from a source exterior thereto, such as the water supply pipe of a dwelling or office building, the admission of water to the tank being regulated so as to maintain the water at a predetermined level therein, the regulating means serving also to disable and enable the heating means for the sterilizing tanks.

One of the main objects of my invention is to provide a sterilizing means of the character stated provided with a water supply pipe opening into the water tank, the admission of water from this pipe to the tank being regulated by means responsive to the water level in the latter. A further object is to provide means actuated by the regulating means for disabling and enabling the heating means for the sterilizing tanks. Another object is to provide a structure in which the regulating means and associated features are so related as to produce a compact structure particularly well adapted for use with sterilizers. It is also an object of my invention to provide simple and efficient means for maintaining the water in the sterilizing tanks at the most efficient level for sterilizing purposes. Further objects and advantages of my invention will appear from the detailed description.

In the drawings:—

Figure 1 is a fragmentary vertical sectional view through a sterilizer, taken from front to back thereof, illustrating my invention as applied, parts being broken away;

Figure 2 is a section taken substantially on

line 2—2 of Figure 1, on an enlarged scale, parts being shown in elevation;

Figure 3 is a section taken substantially on line 3—3 of Figure 2; and

Figure 4 is a diagram of the connections of the heating units for the sterilizing tanks.

I have illustrated my invention, by way of example, as applied to a sterilizer comprising a cabinet 1 having a removable top 2 provided with suitable openings therethrough for receiving and supporting sterilizing tanks 3 and 4, tank 3 being adapted for reception of instruments to be sterilized and tank 4 being adapted for reception of towels, dressings, and similar articles to be sterilized. The construction of the cabinet and the cover therefor, as well as of the tanks 3 and 4, is similar to that of my above identified co-pending application and need not be described here in detail, it being sufficient to note that suitable means is provided for supporting the sterilizing tanks. 75

Each of the sterilizing tanks has associated therewith a heating unit 5 (Figure 4), this unit comprising two pairs of resistance elements *a* and *b*, the elements *a* and *b* of each pair being connected in multiple. Resistance element *a* of one pair is connected in series with resistance element *b* of the other pair, and with a thermostat 6 of known type. This thermostat acts, when the water in the sterilizing tank has been heated to a predetermined high temperature, to open the circuit of the elements *a* and *b* associated therewith, thus reducing the heating capacity of the unit 5. Pilot lights 7 are connected across the respective heating units 5, and the several circuits for these units have fuses 8 interposed therein, these fuses being carried by a fuse block 9 of known type. Manually operated switches 10, of suitable type, are provided for controlling the circuits of the heating units 5. Current is supplied to the heating units by mains 11 and 12, and a mercury tube switch 13 is interposed in main 11. Normally the switch 13 is closed so that by closing the switches 10 the heating units 5 may be rendered operative, selectively. If the water in the sterilizing tanks falls below a safe level, the switch 13 is automatically opened, thus disabling the heating units so as to prevent injury to the sterilizer tanks, such as would occur if such tanks were heated with insufficient or no water therein. The various connections of the heating units are described in more detail in my co-pending application previously referred to, and need not be described here in greater detail, it sufficing to note that the switch 13 is a main 105

110

control switch for disabling and enabling the heating units.

Conveniently, the heating units comprise two members 5a (Figure 1) of known type, each of these members including one pair of resistance elements *a* and *b* suitably mounted upon and enclosed by insulating material. Members 5a are pressed firmly against the bottoms of the sterilizer tanks by pressure plates 14. Each of the plates 14 is provided, adjacent each end thereof, with a depending boss 15 suitably recessed for the upper end of a pressure screw 16 which threads through a boss 17 of a channel bar 18, the ends of which rest upon upturned terminal elements of straps 19 secured to and depending from the sterilizer tanks. This provides simple and efficient means for securing the heating units in operative relation to the sterilizer tanks. A tank securing strap 20 in the form of a double U is suitably secured to lugs 21 carried by top 2 of the cabinet. This strap passes about and beneath the sterilizer tanks and receives screws 22 passing therethrough, these screws threading into the channel bars 18 and cooperating therewith and with straps 19 to anchor the sterilizer tanks to the top of the cabinet. Each of the sterilizer tanks has associated therewith a suitable cover and means for opening and closing the same, which need not be illustrated nor described in detail here, it being sufficient to note that the sterilizers have suitable covers and operating means therefor.

A water tank 23 depends from top 2 of the cabinet adjacent the back thereof, this tank being conveniently formed integrally with the top. A cup-like receptacle 24 is suitably secured to, and depends from, the tank 23 at one end thereof, this receptacle communicating with the tank through an opening 25 therein. Receptacle 24 opens into the adjacent end of tank 23, through the bottom thereof, by means of an elbow 26 extending from the receptacle remote from the upper end thereof, the upper end of this elbow being suitably secured to a boss 27 formed on the tank and provided with an opening 28 into the tank. Receptacle 24 is provided, at the bottom thereof, with an outlet or drain opening 29 and, a short distance from its upper end, with a nipple 30 defining an outlet opening 31. This nipple is connected by a union 32 with a pipe 33 which communicates, by means of suitable connections 34, with the sterilizer tanks through the bottoms thereof. A nipple 35, which defines the drain opening 29, extends from the bottom of receptacle 24 and is suitably connected to a drain pipe 36, the forward end of which extends into the valve casing 37 with which communicates connection 34 of the forward sterilizer tank 3. The outlet from this latter connection 34 and the outlet from the drain pipe 36 are controlled by suitable valves disposed within casing 37, such valves having stems 38 and 39 projecting forwardly of the casing. The casing 37 terminates, at its lower portion, in a drain spout 40. Normally the valves are closed, and by opening the valves 65 the tanks and the receptacle 24 can be drained, selectively, as desired or as conditions require. If desired, the receptacle 24 may have suitable heating means associated therewith at the upper portion thereof, as disclosed in my above identified co-pending application, such heating means facilitating precipitation of minerals from the water in receptacle 24, the substances thus precipitated being readily drained from the lower portion of the receptacle by means of the drain

75 pipe 36 and the associated valve and spout 40. This provides means for conditioning the water preliminary to its entry into the sterilizer tanks so as to eliminate or reduce the deposition of minerals therein.

80 Water is supplied to the tank 23 by means of a water supply pipe 41 which is suitably connected to a source of supply of water under pressure, preferably the water supply system of a dwelling or office building. The pipe 41 is connected by a union 42 to a nipple 43 suitably secured through the bottom of tank 23, adjacent one end thereof, in a known manner. Nipple 43 depends from a fitting 44 of known type in which operates a valve 45, also of known type, for controlling admission of water to the tank. This valve is suitably connected to a link 46 pivoted at one end, at 47, in a bracket 48 extending upwardly from the fitting 44 at one side thereof. The other end of link 46 is connected by a clevis structure 49 to one end of a lever 50 pivoted at 51 in a bracket 52 extending upwardly from fitting 44 at the opposite side thereof. A float 53 is suitably connected at 54 to the other end of lever 50. This float is responsive to the water level in tank 100 23 and operates the valve 45 so as to regulate admission of water to the tank in such manner as to maintain the water therein at a predetermined level. An overflow nipple 55 is suitably secured to the bottom wall of the tank and is 105 connected by a union 56 to a pipe 57 conveniently connected to the sewer. The overflow nipple 55 and pipe 57 prevent flooding in the event the valve 45 fails to close properly when the water reaches the predetermined level in the tank, 110 which normal and predetermined level is indicated by the line *x-x*.

115 For the most efficient operation of the sterilizers, it is important that the water in the sterilizer tanks be maintained at such a level 120 therein that each of the sterilizer tanks contains only that amount of water which is most efficient for sterilizing purposes. This has the advantage of expediting the sterilizing operation while also effecting a material saving in the fuel 125 or electricity utilized for heating purposes, since the amount of water required to be heated at any given time is the minimum amount required for efficient sterilizing. With this object in view, the sterilizing tanks are so disposed relative to the water tank that, when the water in the latter is at normal level, the amount of water 130 in each of the sterilizing tanks is the minimum amount required for efficient sterilizing. In this connection, since the water supply pipe 41 is connected to a constant source of supply of water under pressure, close regulation of the water level by means of the float regulated valve is possible, which assures that the water level within the sterilizing tank is maintained at all times and 135 without appreciable variation therein. This materially adds to the efficiency of the sterilizers and is a distinct improvement over the apparatus of my co-pending application in which it is necessary that there be an appreciable drop in level 140 in the water tank, accompanied by a corresponding drop in water level in the sterilizing tanks, before the supply of water in the water tank is replenished and again restored to normal level. I consider this close regulation of the water level 145 in the tanks of considerable importance as contributing materially to the efficiency of the sterilizers.

150 The main control switch 13 is mounted in spring clips 58 carried by a mounting plate 59,

which plate is adjustably mounted by pin and slot means 60 upon a base plate 61 pivoted at 62 on a bracket 63 suitably secured to and depending from the bottom of tank 23. Flexible leads 64

5 are connected to the terminals of the mercury tube switch 13, one of these leads being also connected to a suitable terminal carried by a connecting block 65 which is suitably mounted upon the bracket 63. The other terminal 64 is connected to the positive main 11 of Figure 4 in a suitable manner. The block 65 also carries a terminal 66 which is suitably connected, in a known manner, to terminal 67 to which lead 64 is connected, the terminal 66 being connected by lead 11a to switches 10. In this manner the switch 13 is connected in series with the positive main, as in Figure 4. By rocking the base plate 61, the switch 13 is tilted to open or close the circuit, thus disabling or enabling the heating units 10 of the sterilizing tanks, in accordance with the water level therein.

A tube 68 is suitably secured through the bottom of tank 23 and extends upwardly therein well above the normal water level. A connecting rod 69 is slidable through tube 68. The lower end of rod 69 is suitably secured, as by means of a set screw 70, in a clevis 71 which is pivoted at 72 to one corner of plate 61. The upper end portion of rod 69 is shaped to provide a hook element 73 which engages over and about lever 50. Rod 69 is thus connected to the lever for movement therewith. When the water in tank 23 is at the predetermined and normal level therein, the switch 13 is in horizontal position, or closed, so as to complete the circuit therethrough. If the water in tank 23 falls materially below normal level, float 53 is lowered, this causing downward movement of rod 69 due to movement of lever 50 with the float. This movement of rod 69 rocks plate 61 in a counterclockwise direction, as viewed in Figure 2, and tilts the switch 13 sufficiently to open the circuit therethrough, thus disabling the heating units of the sterilizing tanks. The downward movement of float 53 results in opening of valve 45 and the admission of water to tank 23. When the water in this tank has been restored to its normal level, float 53 returns to normal position and rod 69 acts to return plate 61 to normal position, thus again closing the circuit through switch 13. Ordinarily, the normal water level will be maintained in tank 23 and the switch 13 will remain closed. If the valve 45 should fail to open properly, or for any other reason the proper supply of water to the tank 23 is interfered with, and the water in this tank falls materially below normal level, the switch 13 will be opened in the manner described, thus disabling the heating units of the sterilizing tanks and preventing injury to the latter such as would occur if the heating units remained in operation with an inadequate amount of water in the sterilizer tanks.

The control switch 13 is operated by the means which regulates the admission of water to the tank 23. This is advantageous since, under ordinary conditions, the control switch is maintained in closed position and the water in the tank is closely regulated so as to be maintained at the most efficient operating level therein. In the event the water in the tank 23 drops materially below the predetermined level therein, the means for regulating the admission of water to the tank operates through the rod 69 and associated parts, to open the main control switch 13 in the manner previously described.

The tank 23 is normally closed by a removable cover 75 having a depending flange 76 fitting about the upper portion of the tank. This cover gives ready access to the interior of the tank and to the parts disposed therein, as desired or as conditions may require. The provision of the pipes 33 and 36, in conjunction with the main valve casing 37 and drain faucet 40, and associated parts, is advantageous as facilitating draining of the tanks or of the receptacle 24, selectively.

What I claim is:—

1. In sterilizing means, a sterilizing tank, heating means therefor, a water supply tank communicating with the sterilizing tank for supplying water thereto, means for supplying water to the water tank, means responsive to the water level in said water tank for regulating the admission of water thereto and for normally maintaining the water therein at a predetermined level, and means connected to and actuated by said regulating means for disabling said heating means when the water in the water tank falls materially below said predetermined level, and enabling the heating means when the water in the water tank is restored to operating level therein.

2. In sterilizing means, a sterilizing tank, electrical heating means therefor, a water supply tank communicating with the sterilizing tank for supplying water thereto, a water admission pipe opening into the water tank, a valve controlling said pipe, float means responsive to the water level in the water tank and operatively connected to the valve for maintaining the water in said water tank at a predetermined level therein, a control switch for said heating means, and disposed beneath the water tank, a tube opening through the bottom of said water tank and extending above the normal water level therein, and a connecting member extending through the tube and connecting the float means to the switch for opening and closing the latter in accordance with fall of the water in the water tank materially below said predetermined level and restoration of the water in said water tank to normal level therein.

3. In sterilizing means, a sterilizing tank, electrical heating means therefor, a water supply tank communicating with the sterilizing tank for supplying water thereto, a water admission pipe opening into the water tank, a valve controlling said pipe, a lever connected to the valve for opening and closing the latter, a float within the water tank and connected to the lever for regulating closing and opening of the valve for maintaining the water in said water tank at a predetermined level, a bracket depending from the tank, a control switch for the heating means pivoted on the bracket, a tube opening through the bottom of the tank and extending above the normal water level therein, and a connecting rod slidable through the tube and connecting the lever and the switch for opening and closing the latter in accordance with fall of the water in the water tank materially below said predetermined level and restoration of the water in said water tank to normal level therein.

4. In sterilizing means, a sterilizing tank, a water tank, a receptacle extending below the water tank and receiving water from the latter adjacent the bottom thereof, a drain pipe extending forwardly from the lower portion of the receptacle, a pipe extending forwardly from the upper portion of the receptacle and opening into

the sterilizing tank for supplying water thereto, and valve means at the forward ends of the respective pipes for controlling the latter:

5. In sterilizing means, a sterilizing tank, a water tank, a receptacle extending below the water tank and receiving water from the latter adjacent the bottom thereof, a drain pipe extending forwardly from the lower portion of the receptacle, a pipe extending forwardly from the upper portion of the receptacle and opening into the sterilizing tank for supplying water thereto, a valve casing at the forward ends of and common to the pipes, said casing including a drain spout extending therefrom, and valve means associated with the casing for selectively controlling the pipes.

6. In sterilizing means, a sterilizing tank, heating means therefor, a water supply tank communicating with the sterilizing tank for supplying water thereto and connected to an exterior source of supply of water under pressure, means responsive to the water level in the supply tank for regulating admission of water thereto from said source and for normally maintaining the water in said supply tank at a predetermined level therein, a switch controlling said heating means, and operating connections between said regulating means and said switch acting to open the switch when the water in the supply tank falls materially below said predetermined level and to close said switch when the water in said supply tank is restored to said predetermined level therein.

7. In sterilizing means, a sterilizing tank, heating means therefor, a source of supply of water under pressure communicating with said tank, means responsive to the water level in the tank for regulating admission of water from said source and normally maintaining the water in said tank at a predetermined level therein, a switch controlling said heating means, and connections between the regulating means and said switch acting to open the switch when the water in the tank falls materially below said predetermined level and to close said switch when the water in the tank is restored to said predetermined level therein.

8. In sterilizing means, a sterilizing tank, electrical heating means therefor, a water supply tank communicating with the sterilizing tank for supplying water thereto, a water admission pipe opening into said water supply tank, a valve controlling said pipe, float means responsive to the water level in the water tank and operatively connected to the valve for maintaining the water in said water tank at a predetermined normal level therein, a control switch for said heating means, and operating connections between said switch and said float means for closing and opening the switch by movement of the float means in accordance with fall of the water in the water tank below said normal level and restoration of the water in said water tank to normal level therein.
